METHOD AND APPARATUS FOR TRAIN CONTROL

Filed Feb. 15, 1922

Neil D. Preston INVENTOR

UNITED STATES PATENT OFFICE

NEIL D. PRESTON, OF ROCHESTER, NEW YORK, ASSIGNOR TO GENERAL RAILWAY SIGNAL COMPANY, OF GATES, NEW YORK, A CORPORATION OF NEW YORK

METHOD AND APPARATUS FOR TRAIN CONTROL

Application filed February 15, 1922. Serial No. 536,750.

This invention relates to automatic train control systems for railways, and more particularly to a method and apparatus for transmitting or communicating influences from a trackway to a moving vehicle or train, dependent upon the presence and location of another train ahead, and adaptable for the control of cab signals, brake control mechanism, or other safety devices.

Briefly and generally stated, the elemental objects of this invention are to provide a method, and a specific apparatus for practicing such method, by means of which appropriate controlling influences may be communicated to moving trains dependent upon the presence and location of another train immediately ahead, which will act inductively through an intervening air gap without physical contact, will maintain a continuous communication, so that a change in traffic conditions ahead will be instantly manifested and so that the apparatus may be constructed on the principle of failure on the side of safety, and which will not require the use of trackway devices or sources of current other than those commonly used in the present day direct current track circuit block signal systems.

Various other characteristics, features, and advantages of the invention will be in part apparent and in part pointed out hereinafter as the description progresses.

The accompanying drawing illustrates in a simplified and diagrammatic manner one specific embodiment of means for practicing the method and performing the functions of the apparatus constituting this invention, the devices and circuits being illustrated more with a view of making the nature of the invention readily appreciable, than with the purpose of illustrating the exact construction and arrangement of parts preferably employed in practice.

Referring to the accompanying drawing, the track rails 1 of the railroad are divided by insulated joints 2 into track sections or blocks in the usual way, one block B with the ends of the two adjacent blocks A and C being shown. These blocks are provided with direct current polarized track circuits in con-

formity with well-known practice. The parts and circuits associated with the several blocks are the same, and for convenience will be given the same reference characters with distinctive exponents. At the entrance end of each block, traffic being from left to right as indicated by the arrow, is a track relay 3 of the usual neutral-polar type, which is provided with pole changing contacts controlling the connection between a track battery 4 and the track rails at the exit end of the next preceding block in the rear. The cab signal or train control system governed by the influence communicating means constituting this invention may be used with or without the usual trackway fixed signals, and such signals S have been shown conventionally, without attempting to illustrate their control circuits, which may be of any one of the well-known types.

A locomotive, or other railway vehicle, is illustrated conventionally as a pair of wheels and an axle. In accordance with this invention, there are carried by this vehicle, supported, housed, and protected in any suitable manner, detecting coils 5-5^a, which are carried in front of the first pair of wheels and axle of the vehicle, directly over the track rails 1. These coils 5-5^a may be of any suitable shape, and are mounted on a suitable frame supported by anti-friction bearings, so as to be rotatable on an axis extending along the rails. In other words, these coils are arranged so that, when rotated, they will cut the magnetic lines of force or flux which encircle or surround the track while the direct current from the track battery 4 is flowing therein. The detecting coils 5-5^a are provided with commutators and brushes, designated 6-6^a, of suitable construction, corresponding to that commonly employed in direct current generators, to convert the alternating E. M. F. generated in said coils into a uni-directional voltage. These receiving coils 5-5^a are continuously rotated by some suitable instrumentality. In the specific arrangement shown, small direct current motors of the shunt type 7-7^a, connected in multiple, and supplied with current from a suitable battery 8 or other source, are directly coupled

55

60

65

70

75

80

95

100

to the frames or supports for the coils 5—5^a. While under favorable conditions the generated current obtainable in the receiving coils 5—5^a may be employed to actuate an electro-responsive device directly, on account of practical limitations, it is preferred to amplify the voltage manifestations in said coils, so as to obtain an amount and form of energy adaptable for the operation of ordinary relays of the tractive type or equivalent types. For this purpose a thermionic amplifier or relay of the well-known vacuum tube type is preferably employed, although any suitable electro-responsive device with amplifying characteristics may be employed. The thermionic amplifier shown, commonly termed an audion, comprises a filament F, a grid G, and a plate P. Since the characteristics and mode of operation of these audions are well understood in the art, it is deemed sufficient to point out the way in which such characteristics are utilized in connection with this particular invention.

Referring to the specific arrangement shown, two audions 9 and 10 are used. The filament F of each audion is heated by a battery 11 in the usual way. In the plate circuit of the audion 9, energized by a battery 12, is connected a relay R, which may be of the tractive, dynamometer, or other type, best adapted for the particular working conditions under which the invention is practiced. It is contemplated that the contacts or circuit controlling elements of this relay will be biased or counterweighted so as to change as the energizing current of the relay is cut off, or decreased below the hold up value. In the plate circuit of the audion 10, energized by a battery 13, is a similar relay R¹. The contacts for the relays R and R¹ are shown conventionally; and while the selective operation of these contacts may be employed to control cab signals or any suitable form of train control mechanism, or both in a simplified arrangement as illustrated, three lamps, r, y and g, and a device K, are governed in conformity with the energization control of said relays R and R¹. The lamp g may be green or any other suitable color, and when lighted signifies clear or proceed, the lamp y (yellow) signifies caution, and the lamp r (red) signifies stop or danger.

The device K may take various forms, and since its specific construction or mode of operation forms no part of the present invention, it is unnecessary to discuss its operating characteristics in detail, it being noted that, according to the specific arrangement of circuits shown, this device K is one which is maintained inactive while energized, and is set into operation or rendered active when deenergized. The device K, when set into operation, may cause an immediate brake application in any suitable manner, or brake application in case the engineer fails to take

appropriate action, or a brake application dependent upon the vehicle's speed being in excess of some fixed speed limit, or in excess of a speed limit changeable in accordance with the progress of the vehicle. It may be added that, on account of the continuous control characteristics of the influence communicating means constituting this invention, a cyclic train speed control of the type shown and described, for example, in the patent to Simmen, 1,150,309, August 17, 1915, may be employed to advantage.

The control circuits for the lamps r, y and g, and the device K, may be readily traced on the drawing. With the relay R up and the relay R¹ down, the lamp g is lighted and the device K energized, corresponding to clear traffic conditions. With the relay R down and the relay R¹ up, the lamp y is lighted, and the device K deenergized, corresponding to caution conditions. With both the relays R and R¹ down, the lamp r is lighted, corresponding to danger or stop conditions, the device K being still deenergized.

The receiving coils 5—5^a are connected in series, through their commutators 6—6^a, and are connected in the grid circuits of the two audions 9 and 10 in a reverse manner. The circuit connecting the receiving coils 5 and 5^a in series and maintaining a potential on the grid G of the audion 9 with respect to its filament F may be traced as follows:—commencing at the grid G, wires 14 and 15, upper brush of commutator 6^a through the coil 5^a, lower brush of said commutator, wire 16, upper brush of commutator 6, through coil 5, lower brush of said commutator and wires 17 and 18 to the filament F. The coils 5—5^a are so wound and connected that the voltage induced therein, when current flows in opposite directions in the respective track rails, will be cumulative or additive. To illustrate, assuming a certain direction of current flow in the track rails 1 and a certain direction of rotation of the coils 5 and 5^a, these coils are so wound and connected to the commutators 6 and 6^a that the upper brush, for example, of the commutator 6^a will be positive, as indicated, whereas the lower brush of the commutator 6 will be negative. Without tracing the circuits, it can be easily seen from the drawing that the upper brush of the commutator 6^a, assumed for the purposes of explanation to be positive under clear traffic conditions illustrated in the drawing, is connected to the grid G of the audion 9, while the filament F of this same audion is connected to the lower brush of the commutator 6, thereby making the potential of this grid positive with respect to the filament. Similarly, the lower or negative brush of the commutator 6 is connected to the grid G of the audion 10, and the upper or positive brush of the commutator 6^a to the filament of this audion, so that the grid of this audion is nega-

tive with respect to its filament. On account of the reverse connections of the grids of the audions 9 and 10, with any given direction of current in the track rails, the potential on the grid G of one audion is positive, for example, and that on the other audion negative. The various circuits, voltages, and characteristics of the audions 9 and 10 are selected or proportioned such that a positive potential on the grid of either audion 9 or 10, will allow sufficient current to flow in the plate circuit of that audion to pick up and hold up the corresponding relay R or R¹; whereas with a substantially zero potential on said grid, the plate current is so reduced as to allow the corresponding relay to drop away in response to its biasing force. On account of the well-known characteristics of the vacuum tube amplifier or audion, when the grid potential is reversed and becomes negative with respect to its filament, the current is less than when the grid is at a zero potential and much less than when at a positive potential.

From consideration of the polarized track circuits illustrated, it will be evident that, under clear traffic conditions, the current in the track rails of each block will flow in one direction in one rail, and in the opposite direction in the other rail, as indicated, for example, by the arrows a. When there is a train in the block, as the block C, the track relay 3¹ of that block is caused to drop its armature in the usual way, and this reverses the connections of the track battery to the track rails of the block next in the rear, as the block B, so that the currents in track rails of this block in the rear, while still flowing in opposite directions relatively to each other, are in the opposite direction to that under clear traffic conditions. With a train in a block, its wheels and axles form a shunt of very low resistance, so that very little, if any, current will flow through the track rails in front of a vehicle entering that same block. Thus, under clear traffic conditions, the voltage induced in the coils 5-5^a is of one polarity, causing one relay R to pick up and the other relay R¹ to drop; under caution traffic conditions, the polarity of the voltage generated in the coils 5-5^a is reversed, reversing the potentials on grids of the audions 9 and 10 and causing the relay R to drop and the relay R¹ to pick up; and under dangerous traffic conditions practically no voltage is generated in the coils 5-5^a, reducing the potential on the grids of the audions 9 and 10 to zero, and causing both relays R and R¹ to drop. In this way, there are received on the car the three indications of clear, caution, and stop; and these indications may be used in any suitable manner, as indicated above, to control the brakes of the vehicle and regulate its movement arbitrarily, or dependent upon speed or other condition. These three indications of clear, caution, and

stop received on the car correspond with those given by the trackway signals of the ordinary block signal system. An engineer may, of course, see a fixed block signal some distance before he reaches it and tell if it gives a clear, caution, or danger indication, whereas the cab signal indications afforded by the system of this invention do not change until the train actually passes the block entrance or a corresponding control point. These cab signal indications, however, strictly conform with the changing traffic conditions, a change to a more favorable indication taking place automatically and instantly as soon as traffic conditions ahead clear up. It is noted that one audion and relay are sufficient for two indications, and since certain types of speed governed brake control mechanism, require only two indications for their proper control, it is evident that an adequate train control system may be devised in accordance with the principles of this invention with the use of one relay and one audion alone.

It will be observed that this invention provides the reception of the desired controlling influences without the addition of any track devices or source of energy. The influence is communicated continuously, and the various circuit connections are such that interruption thereof, depreciation or failure of the car-carried batteries, crossings between wires, and other defects likely to occur, will all cause cessation of the communicating influence and produce an effect on the side of safety. Also, such continuous control possesses the desirable characteristic of instantly manifesting on a following car at any point in a block a change in traffic conditions in the next block in advance. For example, if the train is in the block B, and danger conditions in the block C are indicated by the dropping of the track relay 3¹, apparatus on the following train will instantly respond as soon as the conditions in block C change from danger to caution or clear, entirely irrespective of the position of said following train in the block B. This latter characteristic is obviously of great value in speed control systems in which a restriction upon train movement is imposed and continued until an automatic release or restoration is obtained from the trackway; and the indications of the cab signal devices, if used, correspond correctly to the indications of the trackway fixed signals.

It will be appreciated that the relative sizes and proportions of the parts and electrical constants of the various circuits are susceptible of considerable adaptation in practice, in order to obtain the most favorable results under a given set of working conditions; and consequently, no attempt has been made to show and describe any specific arrangement. It should be understood, however, that two

or more audions in cascade, with appropriate adjuncts, may be used to amplify, modify, or otherwise adapt the energy in the receiving coils 5—5^a for the operation of the control of electro-responsive means. Two receiving coils 5—5^a carried one over each track rail are shown, so connected as to act cumulatively, and this is done in order to minimize the chance of false operation due to stray currents in track rails, it being evident that stray currents flowing in opposite directions in the respective track rails, and of a sufficient magnitude to cause false operation of the train control equipment, will likewise have a tendency to produce false operation of the regular track relay. Putting it another way, it may be said that the train control apparatus will not be improperly affected by any stray currents in the track rails which would not also tend to produce improper track circuit operation, a condition which would have to be in some way remedied.

Since, the length, ballasted conditions, battery voltages, and the like, for different direct current track circuits now in common use on railroads are somewhat variable, it may be necessary in practicing this invention to modify these factors in some cases in order to obtain satisfactory operation of the train control system. For example, so-called cut-sections may be used for long blocks, the voltage or type of track battery changes, the resistance of the track relays or their connections increased to allow a higher inter-rail potential at the relay end, and similar adaptations made in existing track circuits in a manner evident to those skilled in the art, so as to obtain the desired value of current in the track rails in front of a train on a given track circuit at the different points in the travel of such train. With proper provision for amplification, however, the current in the track rails may be very small; and except for the danger of possible interference by feeble magnetic fields near the track rails from other sources than the proper current, no arbitrary amount of current in the track rails is necessary to practice the invention. The detecting or receiving coils 5—5^a are preferably used without iron cores so as to avoid possible difficulty with the effects of residual magnetism, and similarly the instrumentality driving these coils, which has been shown for simplicity as small direct current motors, will likewise be designed or protected in the practical application of the invention to avoid such interference.

It is pointed out in this connection that a magnetic field through both of the coils 5—5^a in the same direction produces no effect, since the voltages generated in these coils in such a case will oppose each other. In short, while appropriate design and selection of electrical constants are necessary in practicing the invention under varying working conditions

existing in practice, as a general proposition, the system of communicating influences in the manner characteristic of this invention is adaptable to direct current track circuits as now commonly used, thereby enabling the application of the train control system to railroads without material change in their track-way equipment, providing additional sources of current, or adding to the trackway anything that may interfere with their rolling stock clearances.

The specific construction and arrangement of parts and circuits shown and described are obviously susceptible of much adaptation and modification without altering the nature and characteristic of the invention; and I desire to have it understood that this drawing and specification are merely an illustrative disclosure of one particular type of means for practicing the method and carrying out the functions of the apparatus constituting my invention.

What I claim is:—

1. The method of communicating influences to moving trains in conformity with traffic conditions, which consists in supplying to the track rails a direct current of one or the other polarity, converting the field of flux around the track rails created thereby into a current of like polarity on a moving car, and amplifying such current on the car and utilizing it to govern safety mechanism in conformity with the existing polarity of current in the track rails.

2. The method of communicating influences to moving trains for train control purposes, which consists in supplying to the track rails normally a direct current of one polarity, reversing the polarity of such current for a limited distance in the rear of a train, detecting such current without physical contact, and governing safety mechanism on a following train in accordance with such change of polarity.

3. The method of communicating influences to moving trains for train control purposes, which consists in continuously supplying a control current to a moving car by the presence of a continuous direct current in a conductor disposed along the path of movement of said car, amplifying such current and utilizing it for governing cab signals or train control mechanism.

4. The method of communicating influences to moving trains for train control purposes, which consists in supplying a control current continuously to a moving car without physical contact by a continuous direct current in a conductor disposed along the path of movement of the car, modifying the direct current in the conductor at times to correspond with the varying traffic conditions, and utilizing variations in the current on the car for cab signals or train control purposes.

5. The method of communicating influences to moving trains for train control purposes, which consists in changing the existence and the direction of flow of direct current in a conductor disposed along the path of movement of a vehicle, producing without physical contact with said conductor a current in a circuit wholly on the car which depends upon and varies with the presence and also polarity of said direct current in said conductor, and utilizing such flow of current in said car carried circuit for train control purposes. 70
10. A method of providing the control influences suitable for cab signals or train control purposes, which consists in dividing the track rails into insulated track sections, supplying direct current to the rails of each track section the polarity of which is dependent upon the presence or absence of a train in the next track section in advance, and producing in a circuit wholly on a following car a current corresponding to and dependent upon the presence of such current in the track 75 rails, and utilizing the current in the car-carried circuit for train control purposes. 80
15. A method of providing the control influences suitable for cab signals or train control purposes, which consists in dividing the track rails into insulated track sections, supplying direct current to the rails of each track section of a polarity dependent upon the presence or absence of another train in the next track section in advance, converting 85 the field of flux around the track rails into a current on a following vehicle, amplifying said current on the following vehicle, and utilizing the amplified current to govern cab signals or train control devices. 90
20. The method of communicating train movement influences from the trackway to moving vehicles for cab signals or train control purposes, which consists in forming a series of normally closed circuits, partly on the track and partly on the moving car with an interposed air gap, and supplying said circuits with direct current and providing therein devices for detecting and amplifying a constant field of magnetic flux. 95
25. In a system of cab signals or train control for railroads, the combination with polarized direct current track circuits, of means on the car for producing without physical contact with the track rails a derived voltage at all times corresponding to the existence and polarity of the current in said track circuits. 100
30. In a system of cab signals or train control for railroads, the combination with a track divided into track sections each having a polarized direct current track circuit, of automatic means on the car for detecting and amplifying the effect of the current of said track circuits flowing in the track rails. 105
35. In a system of cab signals or train control for railroads, the combination with a conductor along the track in which continuous direct current is flowing, means on the moving car detecting the field of flux created by such current, a device to be governed, and amplifying means controlled by the detecting means for governing said device. 110
40. In a system of cab signals or train control for railroads, the combination with track rails of the railroad track in which continuous direct current is flowing, of car-carried means tending to assume an active condition and maintained inactive by a local source of current on the car controlled by the direct current in the track rails without physical contact. 115
45. In a system of cab signals or train control for railroads, the combination with a track rail carrying continuous direct current of one polarity, of car-carried means for detecting the flow of said current without physical contact, a device to be governed, and amplifying means responsive to the detecting means for governing said device. 120
50. In a system of cab signals or train control for railroads, the combination with a track rail carrying direct current, car-carried means comprising detecting and amplifying devices responsive to the presence and polarity of said current. 125
55. In a system of cab signals or train control for railroads, the combination with a track rail and a source of direct current, track circuit control means controlling the connections between said source and the track rail, and means for amplifying and detecting the flow of current in said rail without physical contact. 130
60. In a system of cab signals or train control for railroads, the combination with a sectionalized railway track, each section being supplied with direct current of a polarity dependent upon traffic conditions, of a controllable device on a car tending to assume its active condition, and means responsive to the presence and polarity of the current in the track rails without physical contact for governing said device said means converting by electro-magnetic induction the magnetic field of said current in the track rails into an electrical difference of potential. 135
65. A train control system comprising, a pair of track rails and a source of direct current connected thereto, and voltage producing means on a car disposed in front of first pair of wheels and axles, and responsive to the flow of said current in said track rails. 140
70. Car apparatus for train control systems comprising, a constantly rotating coil carried relatively close to and above the track rail on which the car runs to cut the magnetic flux produced by current flow in said rail. 145
75. Automatic means for detecting the presence of direct current in the track rails. 150

on which vehicles travel comprising, means carried by the car in front of its first pair of wheels and axle for producing a difference of potential corresponding to the magnetic field around said track rails which is produced by the flow of direct current therein, and biased electro-responsive means and a car-carried source of current controlled by said difference of potential.

20. Influence communicating means of the character described comprising, in combination with a conductor on the trackway carrying current, of car-carried apparatus comprising, a coil in the field produced by the current flow in said conductor, means for rotating said coil, a commutator, a relay, and amplifying means connecting said coil and relay.

21. In a train control system, the combination with a conductor disposed along the path of travel of the vehicle and carrying direct current, and means on a vehicle for detecting without physical contact the existence of such current in the track rails comprising, a generating coil, an amplifying means and an electro-responsive device.

22. In a train control system, the combination with the rails of track sections in which direct current flows in opposite directions under clear and caution traffic conditions, means on a car for changing the field of flux of such current into a potential, safety mechanism on the car, and amplifying means responsive to said potential for governing said safety mechanism.

23. A system of continuous inductive control for railway vehicles comprising, in combination with polarized direct current track circuits, detecting and amplifying means on the vehicle governed by the presence and direction of flow of said current in the track circuits.

24. A system of continuous inductive control for train control systems comprising, the combination with detecting and amplifying means on a car responsive to a constant uni-directional magnetic field, of track circuit control means for supplying such field to the car-carried means at all points in the travel of the car.

25. A system of inductive continuous control for cab signal and train control systems characterized by the detection and amplification of the effect of continuous direct current in a conductor along the path of movement of the vehicle without physical contact.

26. In a cab signal or train control system for railroads, in combination with a sectionalized railroad track, a battery for each section, means acting when a given section is not occupied to connect the battery of the section next in the rear across the track rails at the exit end thereof, means carried on the car relatively close to and

over each track rail in front of the first pair of wheels and axles of the car for producing a uni-directional voltage of a definite polarity which is derived from the current flow in said track rails, and means on the car including a car-carried source of energy and governed by said voltage.

27. In a train control system, a track divided into sections, traffic controlled means automatically applying a uni-directional difference of potential across the track rails of each section at its exit end to produce a direct current, car-carried electro-responsive means and a source of energy on the car connected thereto, and means carried by the car over a track rail and acting automatically to change the flow of current from said source to the electro-responsive means in correspondence with the direction of said direct current in the track rails without circuit interruptions.

28. In a train control system, the combination with a line of track rails in which direct current flows in opposite directions, and means carried on the car in front of the first pair of wheels and axles thereof and cooperating with the magnetic field produced by the flow of said current in the track rails for producing inductively a difference of potential on the car having a predetermined polarity corresponding to the direction of flow of said current in said track rails.

29. In an automatic train control system for railroads having track sections divided into blocks each having a track battery connected across the track rails at one end, car apparatus comprising a relay, a source of current for energizing said relay, a vacuum tube amplifier having its plate circuit connected to said relay, and means disposed in inductive relation to said track rails in front of the first pair of wheels and axle of the car and responsive to the constant uni-directional magnetic field produced by the current flow in said track rails from said battery for imposing a corresponding potential on the grid of said amplifier.

30. In a system of cab signals or train control for railroads, the combination with an insulated track section, a source of direct current, and automatic means for connecting said source across the track rails at one end of said section thereby producing a flow of constant uni-directional current in the track rails; of car-carried means for producing without physical contact a voltage in a car-carried circuit which is derived from and corresponds to the flow of said current in the track rails afforded by said trackway source.

31. In a system of the character described, the combination with the track rails of a track section in which current of a predetermined polarity flows in opposite directions, of a car-carried element rotating in

70

105

110

115

120

125

130

the magnetic field of the current in said track rails and generating a voltage of corresponding polarity.

32. In a system of the character described, an insulated track section, a source of current connected across the track rails of said section at one end thereof, and car-carried conductors maintained in constant motion on the car in the magnetic field produced around the track rails by the flow of said current therein, said conductors generating a voltage derived solely from such current flow.

33. In a cab signal or train control system for railroads having tracks divided into track sections, each section having continuous direct current flowing in opposite directions in its track rails under certain traffic conditions, car-carried means having an inherent tendency to assume its active controlling condition and automatically maintained inactive by the effect of voltage in a car-carried circuit derived from the flow of said direct current in the track rails without physical contact with said track rails.

34. In a system of the character described, the combination with a track section having direct current flowing in opposite directions in its track rails, car-carried apparatus comprising a plurality of circuits to be controlled, electro-responsive means having a tendency to open all of said circuits and operable by unidirectional voltages of different polarities to maintain certain of said circuits closed in conformity with the polarity of said voltages, and means for producing on the car without electrical connection to the track rails unidirectional voltages which are derived from the flow of said direct current in the track rails and have related polarity.

35. In a train control system, the combination with a track section having current flowing in opposite directions in its track rails under certain traffic conditions, car-carried apparatus comprising a relay, an audion controlling said relay, and means for applying to the input circuit of said audion a unidirectional voltage derived solely from the magnetic field of said current flow in the track rails.

36. In a train control system for railroads having track sections in which direct current of different polarities flows in opposite directions in the track rails, car-carried apparatus comprising two three-element vacuum tube amplifiers, and means varying the grid potentials of said amplifiers in the opposite sense to correspond with the polarity of the direct current flowing in the track rails.

37. In a system of the character described, the combination with a track rail in which current flows, of a coil, and a commutator on a car constantly rotated in the field produced by such current flow.

38. Car apparatus for train control systems

comprising, a coil in front of the first pair of wheels and axle of the car and disposed over one of the track rails on which the car runs, a constantly rotating commutator connected to said coil, a thermionic device having its input circuit connected to said commutator, and an electro-responsive device connected to the output circuit of said device.

39. The method of giving on a moving railway vehicle at all points in its travel any one of a plurality of control influences suitable for cab signals or train control purposes, which consists in applying a uni-directional electro-motive-force across the track rails at the exit end of an isolated track section so as to cause a flow of direct current in opposite directions in said track rails, varying the polarity of said electro-motive-force for each track section in correspondence with the presence or absence of other trains ahead, and producing on a vehicle at all points in its travel in each track section and without electrical contact with the track rails a voltage corresponding to and derived from the flow of said direct current in the track rails of that section.

40. In a train control system, the combination of a railway track, a vehicle thereon, said track divided into blocks, means controlled by traffic conditions for energizing a rail of said blocks with continuous direct current, means on said vehicle responsive to the current in said rail and amplifying the effect thereof.

41. In a train control system, the combination of a railway track, a vehicle thereon, means for energizing a rail of said track with direct current, a device on said vehicle responsive to the current in said rail and controlling a circuit, means for amplifying the current in said circuit and means for controlling the polarity of the current in said circuit by the polarity of the current in said rail.

42. In combination, a track rail carrying direct current, a train provided with a generating coil disposed to receive magnetic flux due to the direct current in said track rail, means on the train for driving said coil, and train governing apparatus controlled by the current delivered by said coil.

43. In combination, a railway train, generating means located on said train and comprising a rotating armature, means located in the trackway for continuously supplying magnetic flux to said generating means when traffic conditions are safe but not when traffic conditions are dangerous, means located on the train for driving said armature, and train governing means controlled by current supplied by said generating means.

44. In combination, a railway train, generating means on said train having an armature, means located in the trackway for supplying said generating means with magnetic
